DESIGN FOR A MINIATURE AIRPLANE ENGINE

Irwin G. Ohlsson, Los Angeles, and Henry T. Rice, San Gabriel, Calif.

Application June 28, 1937, Serial No. 70,100

Term of patent 7 years

To all whom it may concern:

Be it known that we, Irwin G. Ohlsson and Henry T. Rice, citizens of the United States and residing at Los Angeles, in the county of Los Angeles and State of California, and San Gabriel, in the county of Los Angeles and State of California, have invented a new, original, and ornamental Design for a Miniature Airplane Engine, of which the following is a specification, reference being had to the accompanying drawing, forming a part thereof.

In the accompanying drawing, Fig. 1 is a top plan view of our new miniature airplane engine; Fig. 2 is a front elevation of the engine; and Fig. 3 is a side elevation.

We claim:

The ornamental design for a miniature airplane engine as shown.

IRWIN G. OHLSSON.
